UNITED STATES PATENT OFFICE.

LIONEL M. WOOLSON, OF DETROIT, MICHIGAN, ASSIGNOR TO PACKARD MOTOR CAR COMPANY, OF DETROIT, MICHIGAN, A CORPORATION OF MICHIGAN.

INTERNAL-COMBUSTION ENGINE.

Application filed August 16, 1922. Serial No. 582,265.

This invention relates to internal combustion engines and particularly to means for controlling the speed thereof.

In the use of internal combustion engines in dirigibles, for instance, an attendant or operator is not always at hand because as a rule the engines are arranged at widely separated points on the dirigible and one operator has charge of several engines. In these cases, therefore, it is desirable that the throttle valve or other controlling means may be set at a predetermined point to give the desired engine speed for the particular cruising or running schedule upon which the dirigible is operated. It is also desirable that in event of the oil pressure of the engine falling below a predetermined degree as by a bearing burning out or because the oil supply is low, or in event of the engine racing or running at an excessive speed due to a propeller breaking or something of that sort, the engine will be automatically stopped or brought down to idle running speed, or in other words, that the controller or throttle valve shall be moved to its closed or idling position so that the engine will not continue to run without oil or so that it will not race and pound itself to pieces before the operator can reach it.

It is one of the objects of the present invention to provide simple and automatic means for stopping or bringing down to idling speed an engine that has lost its oil pressure or has exceeded its predetermined maximum speed.

Another object of the invention is to provide speed controlling means for an internal combustion engine, which means may be set to any desired position within its range and which means is acted upon directly by the oil pressure to retain it in that position.

Another object of the invention is to provide a speed controlling means for an internal combustion engine which means is retained in its set position by oil pressure acting directly upon it and which oil pressure is adapted to be lowered by excessive speed of the engine.

Other objects of the invention will appear from the following description taken in connection with the drawings, which form a part of this specification, and in which:

Fig. 1 is a somewhat diagrammatic view showing a part of an internal combustion engine and a speed controlling means con-

nected therewith and made in accordance with this invention;

Fig. 2 is an enlarged longitudinal section through the governor part of this invention and adjacent parts of the engine crank case;

Fig. 3 is an enlarged elevation of the hand controlling device;

Fig. 4 is a vertical section substantially on the line 4—4 of Fig. 3;

Fig. 5 is a transverse section on the line 5—5 of Fig. 3; and

Fig. 6 is a transverse section on the line 6—6 of Fig. 3.

Referring to the drawings 10 represents the crank case of an internal combustion engine and 11 is the intake conduit of such engine, a throttle valve 12, operating by an arm 13, being shown as the means for controlling the supply of mixture passing to the engine and consequently for controlling the speed of the engine.

Mounted at a suitable point with relation to the engine is a support 14, shown in Fig. 4, upon which is a bracket 15 having a segment 16 and a pivotally mounted lever 17. This lever is the hand controlling device for the engine throttle and it is provided with an arm 18 which is connected to the arm 13 by a rod 19 or other suitable mechanism. A spring 20 tends to move the lever 17 to throttle closed position, so that the throttle is biased toward this position, and the lever may, of course, be moved by hand against the action of the spring so that the throttle may be opened or closed as desired. A rubber bumper 21 is provided for relieving the shock when the lever is closed abruptly by the spring 20.

Upon the lever 17 is pivoted a latch 22, as at 23 and a spring 24 acting on the end 25 of said latch tends to move the opposite end 26 of the latch 22 into engagement with the notches of the segment 16, as shown particularly in Figs. 3 and 4. Thus the lever 17 may be moved to any desired position and the latch 22 will retain it in that position until the latch is moved against the action of the spring 24. A handle 27 for disengaging the latch and moving the lever is provided. Also, a cover 28 is detachably secured over a part of the latch 22 to give a better appearance to the device.

The tension of the spring 24 is adjustable by a cup 29 which is threaded into a boss 116

30 on the bracket 15 and a nut 31 secures the cup 29 in its adjusted position. The boss 30 also forms the pivot for the lever 17 above referred to.

- 5 In the construction so far described the speed of the motor would be entirely manually controlled. It is desirable, however, that the latch 22 shall be moved from its position in engagement with the segment 16
- 10 at any time that the oil pressure drops below a predetermined point. This is accomplished, in the present invention, by the use of a diaphragm having a direct connection with the latch 22. As shown particularly in Fig. 4, a diaphragm 32 is secured between a part 33 of the bracket 15 and a plate 34, screws 35 securing the plate 34 to the bracket. A rod 36 having its head 37 in direct contact with the center of the diaphragm 32 has its other end extending through the opening in the end 35 of the latch 22 and nuts 38 are arranged on the projecting end of the rod 36 thereby forming an abutment. A spring 39 surrounds the rod 36 between the head 37 and the cup 29 above referred to and this spring is stronger than the spring 24 and consequently tends to move the latch 22 in opposition to the spring 24 and to inoperative position.
- 15 It will be seen, therefore, that with no particular pressure on the diaphragm 32 the spring 39 would move the latch 22 to disengaging position. However, the opposite side of the diaphragm 32 is adapted to receive the oil pressure of the lubrication system of the engine and this is effected by a pipe connection 40. This pipe connection runs down through pipes 41 and 42 to a pump 43 the inlet of which pump is arranged in the lower part of the crank case of the engine so that the pressure of oil produced by the pump will act against the diaphragm 32. As long as this pressure exceeds a certain minimum the diaphragm and
- 20 the spring 24 will retain the latch 22 in engaging position with the segment 16 but if the oil pressure for any reason drops below the established minimum the spring 39 will overcome the diaphragm pressure as well as the pressure of the spring 24 and move the latch 22 to disengaging position and the lever 17 will then jump to closed position and bump against the rubber bumper 21.
- 25 The engine oil system is also provided with a conduit or pipe 44 which may lead to the main crank shaft bearings indicated diagrammatically in Fig. 1 at 45 and it may have a branch pipe 46 leading to other bearings 47. The overflow from the bearings is indicated at 48, in Fig. 1 and this overflow, of course, goes back into the crank case where it is picked up and re-circulated by the pump 43 thus keeping a constant pressure in the system.

In Figs. 1 and 2 the crank case 10 of the engine is shown as formed with an opening 49 and a governor casing 50 is supported over the opening. This governor casing supports a pair of separated bearings 51 in which the governor shaft 52 operates and this shaft is shown as driven through a pair of gears 53 from any suitable part of the engine. A shaft 54 telescoping within the shaft 52, as shown particularly in Fig. 2, and a pair of governor arms 55 are pivoted as at 56 to the shaft 52 so that their operating fingers 57 will operate against a flange 58 on the shaft 54 to move the latter lengthwise as the speed of rotation of the shaft 52 increases. The end of the casing 50 is provided with a cover 59 having a hollow extension 60 in which is mounted the governor spring 61. A plug 62 is threaded into the end of the extension 60 and is accessible from the outside of the casing for adjusting the tension of the spring 61. A nut 63 is provided for locking the plug in adjusted position.

The opposite end of the spring 61 rests in a piston valve 64 which closes an opening 65 between the interior of the governor casing 50 and an annular space or compartment 66 formed in the cover 59 around the piston valve 64. This space 66 is in communication with the lubrication system of the engine through a passage 67 and a pipe 68. A hardened steel button 69 is arranged in the end of the piston valve 64 and extends into the interior of the casing 50 in alignment with the movable shaft 54 which also has a steel button 70 on its adjacent end. Preferably the contact surface of the button 69 is flat and that of the button 70 is spherical so that substantially a point contact between the two buttons is obtained.

There are outlet openings 71 and 72 in the governor casing 50 which provide for the flow of oil from the governor casing to the crank case of the engine. It will be understood, however, that the piston valve 64 closes the opening 65 at all normal speeds of the engine so that oil does not normally pass from the chamber 66 to the governor housing except such as may leak past the valve 64.

From the above description it will be seen that failure of the pump 43 to keep pressure in the oil system, such as failure of oil in the crank case or failure of the pump itself, will relieve the pressure on the diaphragm 32 and cause the spring 39 to move the latch 22 to inoperative position. Also, if the engine exceeds its predetermined maximum speed the governor arms 55 will move the shaft 54 against the action of the spring 61 and thus open the piston valve 64 so that oil will flow from the chamber 66 through the opening 65 into the governor casing and thence through the openings 71 and 72 into the crank case. This by-passing of the oil

will, of course, immediately reduce the pressure in the pipe connection 40 of the oil system and the diaphragm 32 will permit the spring 39 to operate the latch 22, and consequently the throttle lever 17 will at once jump to its idle position.

While I have herein described in some detail a specific embodiment of my invention, which I deem to be new and advantageous and may specifically claim, I do not desire it to be understood that my invention is limited to the exact details of the construction, as it will be apparent that changes may be made therein without departing from the spirit or scope of my invention.

Having thus described my invention, what I claim and desire to secure by Letters Patent is:

1. The combination with an internal combustion engine, of a manually operable device for controlling the speed thereof, spring means for moving said device to low speed position, oil pressure controlled means connected directly to said device for holding the latter in any of its adjusted positions, and a governor adapted to vary the oil pressure.

2. The combination with an internal combustion engine, of a manually operable device for controlling the speed thereof, means tending constantly to move said device to low speed position, pressure controlled means acting directly on said device to retain the same in any of its adjusted positions, and a governor adapted to vary the said pressure.

3. The combination with an internal combustion engine having a pressure lubrication system, of a throttle valve biased towards closed position, means to hold said throttle valve in adjusted position, means including a diaphragm operable upon loss of pressure in the lubrication system to release said holding means, a speed responsive device, and means including a valve actuated by said speed responsive device to relieve pressure in the lubrication system upon excessive engine speed.

4. The combination with an internal combustion engine having a pressure lubrication system, of a throttle normally biased to closed position, latch means to hold said throttle open in adjusted position, pressure responsive means in said lubrication system, a device operatively connected to said pressure responsive means adapted to release said latch upon a predetermined loss of pressure in the lubrication system, a speed responsive device, and means actuated by the said device to relieve the pressure in said lubrication system below the said predetermined amount upon excessive engine speed.

5. The combination with an internal combustion engine having a pressure lubrication system, of control means for said engine, a spring urging said control means toward a position to stop the engine, a latch mecha-

nism adapted to hold the control means in adjusted engine-operating position, releasing means for said latch mechanism including a pressure responsive member associated with the lubrication system and operable on a fall of pressure therein, and speed responsive means adapted to relieve the pressure in said lubrication system upon excessive engine speed.

6. In a controller for internal combustion engines, the combination of a support, a lever mounted thereon, a latch mounted on the lever and adapted to hold the lever in various adjusted positions, and a fluid pressure device operating to retain the latch in holding position.

7. In a controller for internal combustion engines, the combination of a support, a lever mounted thereon, a latch mounted on the lever and adapted to hold the lever in various adjusted positions, and a fluid pressure device connected to said support and operating to retain the latch in holding position.

8. In a controller for internal combustion engines, the combination of a support, a lever pivoted on said support, a latch pivoted on the lever and connected to hold the lever in various adjusted positions, and a fluid pressure device connected through said support to the latch for retaining the latch in holding position.

9. In a controller, the combination of a support having an opening therethrough, a lever pivotally mounted on said support, a segment, a latch pivoted on the lever and engaging said segment, a pressure diaphragm mounted on said support, and connections from said diaphragm through the opening in said support to said latch.

10. In a controller, the combination of a support having an opening therethrough, a lever pivotally mounted on said support, a segment, a latch pivoted on the lever and engaging said segment, a pressure diaphragm mounted on said support, a spring plunger in the opening of said support bearing against said diaphragm, and a connection from said plunger to said latch.

11. In a controller, the combination of a support, a lever pivoted thereon, a latch on the lever, a fluid pressed plunger in said support connected to said latch, and a spring to partly offset said fluid pressure.

12. In a controller, the combination of a support, a lever pivoted thereon, a latch on the lever, a fluid pressed plunger in said support connected to said latch, a spring to offset said fluid pressure to a predetermined degree, and a second spring against which said latch may be moved without interfering with the diaphragm.

13. In a controller, the combination of a support, a lever pivoted thereon, a latch on the lever, a fluid pressed plunger in said

support connected to said latch, a spring to offset said fluid pressure to a predetermined degree, and a second spring against which said latch may be moved without interfering with the diaphragm or the first spring.

14. In an internal combustion engine, the combination with the throttle valve thereof, of a latch for holding the throttle valve in a given position, oil pressure means for retaining said latch in position, and a governor connected to control said oil pressure means.

15. In an internal combustion engine, the combination with the throttle valve and the

oil circulating system thereof, of interconnections between said throttle valve and said oil circulating system for retaining said valve in open or partly open position when the pressure in said system is above a predetermined point and for causing the closing of said throttle valve when the pressure of said system falls below said predetermined point, and a governor operated by the engine and connected to release the pressure in said system when the engine reaches a predetermined speed.

In testimony whereof I affix my signature.

LIONEL M. WOOLSON.
